UNITED STATES PATENT OFFICE.

HEINRICH FASSBENDER, OF CHARLOTTENBURG, AND ERICH HABANN, OF BERLIN, GERMANY, ASSIGNEES TO DEUTSCHE TELEPHONWERKE, G. M. B. H., OF BERLIN, GERMANY.

TELEPHONE AND TELEGRAPH SYSTEM WITH AMPLIFIERS.

Application filed May 3, 1921. Serial No. 466,525.

To all whom it may concern:

Be it known that we, HEINRICH FASSBENDER and ERICH HABANN, both German citizens, and residing at Charlottenburg, Germany, and Berlin, Germany, have invented certain new and useful Improvements Relating to Telephone and Telegraph Systems with Amplifiers (for which we have filed applications in Germany dated, respectively, 10 27th August, 1918, and 10th March, 1920, and in England dated 8th March, 1921), of which the following is a specification.

For communication over telegraph and telephone lines amplifiers are used of which 15 the principal portion is a discharge tube and in view of the uni-directional action of these amplifiers it is necessary to provide for the transmission of messages two amplifiers between two points one of the amplifiers serving for the message passing in one direction and the other in the opposite direction. For 20 this purpose hitherto either two parallel lines have been so arranged that each was only used with its amplifier for message in 25 one direction, or only one line was used of which the amplifier was reversed from one amplifying direction to the other which is effected either in accordance with the direction of the messages, or independently of the 30 direction continuously at very short intervals. Both methods are expensive and inconvenient in use.

The subject of the invention is a method according to which only one conductor and 35 two uni-directional amplifiers such as thermionic tubes of known type are provided, the amplifiers being brought in correct operation without any necessity for reversing. The two thermionic tubes are arranged per- 40 manently in parallel line branches and the transmission of the message currents is effected by means of high frequency carrier waves. The separation of the two branches, which is necessary in order to avoid howling, 45 of the amplifiers, is effected by tuning each of the said branches to a different high frequency oscillation whereby each permits only of communication in one direction namely that which is effected at the same frequency 50 oscillation as that of the branch through which it is to pass so that the speaking current in each direction of speaking automatically finds its correct path through the corresponding amplifier.

In the drawings Figures 1 and 2 show dia- 55 grammatic arrangements according to the first method.

In Figure 1 of the drawing there is inserted between the incoming line L_1 and the outgoing line L_2 by means of four trans- 60 formers T_1 T_2 T_3 T_4 a pair of valves R_1 R_2 serving as coupling members, the valve R_1 having its grid circuit connected to the line L_1 or to the transformer T_1 by an oscillating 65 circuit S_1 which consists in the known manner of an induction coil and a tuning condenser. The anode circuit of this valve is connected directly to the transformer T_3 or the line L_2 . The valve R_2 is connected in 70 the reverse manner. The anodes of the valves are indicated by A the grids by G and the glowing cathodes by K. Each of the two valve branches is tuned to a particular 75 high frequency by the oscillating circuits so that it does not allow the other to pass there- 80 through. The current coming from the right for example follows the path, indicated by the arrow, only through the amplifying valve R_2 , the current coming from the left however only passes through the amplifying valve R_1 .

In Figure 2 practically the same arrangement is illustrated with the difference that the tuning oscillating circuits S_1 S_2 are not on the local circuits of the valves but are 85 connected to the distant lines and the trans- 90 formers T_1 T_2 and T_3 T_4 are connected in parallel with these instead of in series as shown in Figure 1. This causes no difference in operation according to the invention.

Having thus described our invention what we claim as new and desire to secure by Letters Patent is:-

1. A high frequency communication line arrangement, comprising an incoming and an outgoing line, two branches in parallel connecting both said lines together, two amplifying thermionic tubes arranged one in each branch, the said tubes being so arranged 95 that the grid of one tube and the anode of another tube are electrically joined to the same line, and tuning means whereby each of the said branches is tuned to another high frequency oscillation and so that communica- 100 tion can be effected in one direction only and this at the particular frequency to which the tube appertaining to this direction is tuned, said tuning also preventing howling. 105

2. A telegraph or telephone line arrangement for high frequency transmission comprising an incoming and an outgoing line, two branches in parallel connecting both 5 said lines together, four transformers having one coil connected to one line, two amplifiers arranged one in each line branch, the amplifiers being so arranged that the anode circuit of one amplifier and the grid circuit 10 of the second amplifier are connected to transformer coils on the incoming line, whilst the grid circuit of the first amplifier

and the anode circuit of the second amplifier are connected to transformer coils on the outgoing line, and tuning means for each 15 of said amplifiers, said tuning means being such that each amplifier is tuned to a different high frequency whereby communication can only be effected through each amplifier in one direction and at the particular high 20 frequency to which the particular amplifier is tuned.

HEINRICH FASSBENDER.
ERICH HABANN.
